UNITED STATES PATENT OFFICE

2,437,287

HEAT EXCHANGE APPARATUS

John E. Woods, Brookline, Mass., assignor, by
mesne assignments, to Standard-Thomson
Corporation, Boston, Mass., a corporation of
Delaware

Application December 15, 1943, Serial No. 514,383

2 Claims. (Cl. 257—2)

1

The present invention relates to heat exchange apparatus and thermostatic control devices therefor, and is more particularly concerned with control devices for radiators, oil coolers, and other heat exchange apparatus of the types suitable for use in aircraft.

Oil coolers and similar heat exchange apparatus for aircraft are usually mounted in ducts extending through the wing. The heat exchanger has channels for flow of the fluid to be cooled and channels for flow of cooling liquid, the two sets of channels being in heat exchange relation. In one widely used form of unit, the channels for the flow of cooling fluid will comprise thin-wall, closely spaced tubes, while the channels for the flow of fluid to be cooled comprise the external inter-tube spaces.

In connection with heat exchange apparatus for aircraft, shutters are frequently provided to diminish the flow of air through the cooling channels at low temperatures. In oil coolers especially, proper control under cold conditions presents a serious problem, since at high altitudes under low power conditions, the oil congeals in the inter-tube spaces of the cooler. In order to free the oil, special warm-jackets with thermostatically controlled valves are provided in the oil circulating system. It is also important to shut off or at least diminish the flow of cooling fluid through the tubes until the temperature rises to the normal operating range.

The use of shutters for controlling the flow of air is attended with a number of difficulties. The shutters are ordinarily operated manually, and therefore do not respond accurately to temperature conditions within the unit. For constructional reasons, they are usually placed at the end of the duct where the air, emerging from the duct, enters the air stream. Hence, any changes in shutter position are likely to introduce aerodynamic disturbances which affect the drag on the airplane. Furthermore, congealed oil in the cooler thaws out progressively from one point to another, and hence the flow of air should be controlled independently through different sections of the cooler, an operation which is impossible with the conventional shutter.

According to the present invention, the cooling fluid channels are provided at the rear of the unit with individual temperature controlled closure devices. These devices operate to close the cooling fluid channels when the temperature of the air is below the normal operating range and to open them as the temperature approaches the operating range. As applied to heat exchange

2

apparatus of the thin tube type, the control members are in the form of tips applied to the individual tubes.

Other features of the invention consist of certain novel features of construction and combinations of parts hereinafter described in the specification and particularly claimed in the claims.

In the accompanying drawings, Fig. 1 is a section through a portion of a heat exchanger illustrating the application of individual control devices according to the present invention, the control devices being shown in closed position; Fig. 2 is an end view of one of the control devices; Fig. 3 is a sectional view of the rear part of the heat exchanger shown in Fig. 1, but with the control devices open; Fig. 4 is a view illustrating the manufacture of the control members; Fig. 5 is an end view of one of the control devices in open position; and Fig. 6 is a sectional elevation of a modified arrangement.

Fig. 1 illustrates a heat exchanger of the general type described in my Patent No. 2,298,996, comprising closely spaced thin-wall tubes 4, mounted at opposite ends in a rear header plate 6 and a front header plate 8. As an example, one construction employs tubes .210" in diameter and about .006" in wall thickness, spaced about .250" on centers. Some units have 3000 or more tubes. At the front ends the tubes may be expanded, as indicated at 10 and as described in my patent. The tubes project slightly through the rear header, as indicated at 12. The tubes are suitably secured to the headers by soldering, by brazing as described in my patent, or in any other suitable manner.

As is customary in devices of this kind, the entire unit is enclosed in a tank or casing having suitable inlet and outlet ports for introducing the oil into the spaces between the tubes 4. The unit is placed in the cooling duct of the plane in such a direction that the air flows through the tubes in the direction of the arrow. In the end of each tube is provided a control member in the form of a tip, indicated generally at 14. Each tip is formed from bendable thermostatic material such as bimetal. The tips are preferably formed by stamping them out of a sheet of bimetal, as illustrated in Fig. 3, each member having a tab 16 so that the member may be rolled up, with a cylindrical base portion, and soldered or welded by the overlapping tab 16. As shown in Fig. 3, the member 14 in flat form is provided with a series of petals 18 of such shape that the petals are in close contact in the completed tip when the metal is at low temperatures.

At higher temperatures the metal bends and the petals open outwardly as shown in Fig. 3. The tips are slipped over the protruding ends 12 of the tubes and are secured in position by soldering, or by means of an adhesive lacquer.

At low temperatures, the control members are closed, as shown in Figs. 1 and 2, substantially blocking the air flow through the tubes except for inconsequential leakage between the petals 18. In an oil cooler, this represents the condition in which the oil is at low temperature, so that the air in the tubes 4 is not heated. As the oil thaws out and increases in temperature, the air is warmed in its passage through the tubes 4 and the warm air passing over the petals 18 causes them to bend outwardly, thereby opening the passage. The amount of opening of the petals is determined by the air temperature. The thermostat characteristics are determined by the fact that the control members should be fully open as indicated by Fig. 3 for normal operating temperatures.

It will be observed that the controls are applied to the individual tubes whereby the control members operate in response to the air flow through their respective tubes. Since the oil necessarily warms up at different rates in the different sections of the cooler, the air temperatures are proper for the different conditions existing in different parts of the unit.

Attention is directed to one important feature of the device. It will be observed from Fig. 3 that if the petals open more than indicated, the petals of adjacent tubes will engage one another and thus limit the extent of opening movement. Except for this feature, the petals of one control member might, under overheating conditions, expand sufficiently to block the passage of air through an adjacent tube or tubes. According to this invention, the tubes are fully open for normal operating temperatures and all higher temperatures.

In the arrangement shown in Fig. 6, a thermostatic member 20 is placed internally of each tube, preferably at about the middle of the tube. This arrangement is important from aerodynamic considerations.

The cooling air upon engaging the front ends of the tubes has some turbulence imparted to it. This turbulence, although it increases the pressure drop, is advantageous in enhancing the heat transfer. In the case of the plain tube unit, as the air progresses along the tube, the turbulence tends to damp out, so that at some intermediate point, the flow becomes laminar, or nearly so. The laminar flow in the remaining travel through the tube contributes little to the heat exchange.

According to the construction in Fig. 6, the thermostatic member 20 in an intermediate portion of the tube obstructs the flow slightly, even when wide open, and thus introduces some turbulence. The turbulence thus introduced improves the heat transfer, although with some unavoidable increase in pressure drop.

It will be understood that the requirements of high heat transfer and low pressure drop are inconsistent and that an improvement in heat transfer is usually accompanied by an increased pressure drop. However, according to the present invention the obstruction of the passage by use of the inserted members is a minimum because the petals, when open, conform to the inside walls of the tube. Hence the turbulence is no more than necessary to prevent the occurrence of laminar flow from the place occupied by the control member to the rear of the tube.

In manufacture, each control member has its base portion coated with adhesive lacquer and is inserted a definite distance into the tube. The petals open and close under temperature changes as in the construction previously described.

Although the invention has been illustrated and described as embodied in a header-type heat exchanger using thin-wall tubes, it will be understood that the invention is not limited to this construction but is applicable to the use of bendable thermostatic leaf members arranged at the rear of individual cooling fluid channels of other types of units.

Having thus described my invention, I claim:

1. In an aircraft oil cooler having tubes for the flow of cooling fluid therethrough, control devices applied to individual tubes at the rear thereof and having bendable thermostatic leaves operating to close the channels at low temperatures and to open for substantially unrestricted flow at normal and higher temperatures, adjacent control devices opening outwardly to engage one another to limit the extent of movement at excessive temperatures.

2. In an aircraft oil cooler having tubes for flow of cooling fluid, control devices for individual tubes at the rear thereof, each device comprising a tip of bendable thermostatic material and having petals capable of closing together at low temperatures and opening outwardly at higher temperatures, the petals of adjacent control devices opening outwardly for engagement with one another to limit the extent of movement at excessive temperatures.

Certificate of Correction

March 9, 1948.

Patent No. 2,437,287.

JOHN E. WOODS

It is hereby certified that errors appear in the printed specification of the above numbered patent requiring correction as follows: Column 1, line 11, for the word "liquid" read *fluid*; line 14, strike out "will"; line 26, for "warm-jackets" read *warm-up jackets*; and that the said Letters Patent should be read with these corrections therein that the same may conform to the record of the case in the Patent Office.

Signed and sealed this 18th day of May, A. D. 1948.
